Patented Mar. 28, 1922.

UNITED STATES PATENT OFFICE.

WILLIAM E. WHITE, OF CHICAGO, ILLINOIS.

CONCRETE INSERT.

1,410,634.

Specification of Letters Patent. Patented Mar. 28, 1922.

Application filed February 16, 1921. Serial No. 445,314.

To all whom it may concern:

Be it known that I, WILLIAM E. WHITE, a citizen of the United States, and resident of Chicago, in the county of Cook and State 5 of Illinois, have invented certain new and useful Improvements in Concrete Inserts, of which the following is a specification.

My invention relates to devices for use in concrete work, and particularly to a novel 10 insert of the kind employed for securing fastening bolts for hangers and similar devices to ceilings.

One of the objects of my invention is to provide means for accommodating a bolt 15 head in position with capacity for a maximum of longitudinal adjustment in devices of minimum size. I am aware of the use of numerous devices having the objects in view of providing for the insertion and removal 20 of a bolt or bolt head together with means preventing the accidental removal thereof. In each case, however, the construction has been such as to limit the effective usefulness 25 of the device in some particular. It has been found in practice that to attempt to utilize any insert in which loose parts are employed, and in which the loose element must be inserted after the insert is located in position, is unsatisfactory, particularly for the 30 reason that workmen do not readily adapt themselves to the manipulations required, the parts become loose or separated, and subsequent users find difficulty in understanding or adapting themselves to the intricacies of 35 operation. In those devices in which no separate part is employed but in which the entrance opening for the bolt head is of less width than the bolt head, the bearing surface for the head when in a vertical position 40 and in an adjusted position which necessitates the head occupying a position above the entrance opening, is limited and the strain exerted on the holding flanges is too great.

45 In my device I have provided a loose holding member which, however, is installed when the parts are manufactured and remains with the insert under all conditions. It is in the form of a keeper of generally U- 50 shape which operates in a vertical guideway which permits it to be raised when the bolt is inserted and to resume its lowermost position by gravity when the bolt head is slid out from under it. Thereafter the bolt 55 may slide from end to end of the box and have a full bearing in whatever position it

is located. Not only this but the keeper and the supporting flanges thereof are so designed that there is no bending strain exerted on any portion of the keeper. 60

The invention will be more readily understood by reference to the accompanying drawings, wherein,

Fig. 1 is a longitudinal sectional view showing the device of my invention in operation;

Fig. 2 is a sectional view on the line 2—2 of Fig. 1;

Fig. 3 is a sectional view on the line 3—3 of Fig. 1; and

Fig. 4 is a perspective view of the keeper which I employ.

In the drawings it will be seen that I provide a box consisting of side walls 10, end walls 11 and top wall 12. Projecting from 75 the top wall is a ribbed anchor member 13, having a terminal enlargement 14, and intermediate webs 15, for a well known purpose.

The box is provided in its lower surface with an open slot, the portion 16 of which 80 is of a width only slightly greater than the diameter of the shank 17 of a bolt to be accommodated therein. The portion 18 of the slot is of a width slightly greater than the width of a standard bolt head 19. The latter slot is of a length substantially equal to its width whereby the bolt head may be inserted with the bolt in a vertical position, as shown by dotted lines in Fig. 1. The metal 20, which adjoins the slot 16, acts as a flange 90 or support for the bolt head and the size of the cavity above the flange is such that the head cannot rotate when in position. The metal 21, which surrounds the opening 18, constitutes a flange which is narrower than 95 the flanges 20 and serves as a support for the keeper 22, best shown in Fig. 4. This member is of U-shape, the opening 23 within which is of substantially the same shape as the opening 16 in the body of the insert. 100 The keeper is supported at its sides and one end upon the flanges 18, and is of sufficient thickness to furnish a rigid support for the bolt head. The keeper is retained in the position shown in the drawings by means of 105 vertical ribs 24, which are spaced apart sufficiently to permit the bolt head to pass readily therebetween.

The bolt is inserted in the following manner. Assuming that the insert has been 110 molded in a body of concrete as shown in Fig. 1, with the bottom of the box flush with

the lower surface of the cementitious material, a bolt is placed vertically and raised to the position shown in dotted lines in Fig. 1, whereupon it is moved toward the left of the 5 slot 16, and the keeper will drop to the full line position of Figs. 1 and 2. Thereafter the bolt may easily be moved from end to end of the box and be supported, and have a full bearing at any point therein.

10 The keeper will preferably be installed when the device is manufactured. It is of such relative size that it may be inserted in an inclined position and permitted to drop into place. Means may also be provided for 15 temporarily retaining the keeper in the box when the devices are shipped. The manner of securing the insert in position on a form and a clip for retaining the keeper in a desired position are illustrated in my co-pending application, Serial No. 445,315, filed of 20 even date herewith.

Obviously the exact form and arrangement of the parts is not essential but I do not wish to be limited except as indicated in 25 the appended claims.

I claim:

1. A concrete insert comprising in combination, a box having a keyhole slot in its 30 bottom wall, a vertical rib internally of said box, said rib being located on a side wall adjacent to the junction of the enlarged and contracted portions of the keyhole slot, and a U-shaped keeper adapted to be accommodated in the space above the enlarged portion 35 of the slot and to be freely movable vertically and be guided by the surrounding walls and said rib.

2. A concrete insert comprising in combination, a box having in its bottom wall a 40 slot one portion of which is widened relative to the remainder, vertical guiding elements in said box adjacent to the widened portion of the slot, and a U-shaped retainer loosely mounted in the space above said enlargement and adapted to be moved vertically 45 and held in its proper position by said guiding elements.

3. In an insert, the combination of a box

adapted to be molded in concrete, said box having a slot in its bottom wall, the slot 50 having a relatively widened and a contracted portion, the widened portion being of a size to permit the insertion of a bolt head, guiding means located internally of the box and arranged vertically adjacent to the widened portion of the opening, and a keeper adapted to be retained in the space above said enlarged opening and to be guided by said guiding elements when moved vertically, said keeper when in its operative position providing a slot of substantially the width and which forms a continuation of the contracted portion of said slot.

4. An insert for concrete work, comprising in combination, a box having in its 60 lower wall a slot provided with a relatively contracted and enlarged portion, flanges being arranged to surround both said portions of the slot, vertical guiding elements arranged internally of the box at a position 70 adjacent to the enlarged opening, and a U-shaped keeper adapted to rest upon the flanges adjacent to the enlarged opening and to be guided in its vertical movement by said guiding elements. 75

5. An insert for concrete comprising in combination, a box having a keyhole slot in its bottom wall, inwardly projecting flanges being arranged on three sides of the enlarged portion of said slot, and a U-shaped 80 keeper mounted in the enlarged opening and adapted to rest upon said flanges.

6. An insert for concrete comprising in combination, a box having a keyhole slot in its bottom wall, inwardly projecting flanges 85 being arranged on three sides of the enlarged portion of said slot, and a U-shaped keeper mounted in the enlarged opening and adapted to rest upon said flanges, the keeper being supported by flanges on three sides 90 thereof and being so arranged that the opening therein forms a continuation of the narrow portion of said slot.

Signed at Chicago, Ill., this 4th day of February, 1921.

WILLIAM E. WHITE.
